NECKTIE CREASE REMOVER

Filed Feb. 11, 1931

Inventor

George B. Ness
By Adam E. Fisher

Attorney

UNITED STATES PATENT OFFICE

GEORGE B. NESS, OF SEATTLE, WASHINGTON

NECKTIE CREASE REMOVER

Application filed February 11, 1931. Serial No. 515,008.

This invention relates to necktie stretchers or crease removers and the main object is to provide a device by the use of which a necktie may be stretched to remove wrinkles and creases therefrom.

Another object is to provide a device of this nature in a simple, efficient and inexpensive form and one upon which the necktie may be readily positioned for stretching.

10 A further object is to provide means in the form of a spread limiting clip whereby the spread of the stretcher may be limited and varied near its end to stretch neckties of any shape.

15 With these and other objects in view the invention resides in the novel construction and arrangement of parts as hereinafter set forth and claimed, reference being had to the accompanying drawing wherein:

20 Figure 1 is a plan view showing the stretcher and the end of a tie positioned thereon the latter being shown in broken lines.

Figure 2 is an enlarged section along the line 2—2 in Figure 1.

25 Figure 3 is an enlarged plan view of the outer end of the stretcher, showing a spread limiting clip in place and showing in broken lines a necktie arranged on the stretcher.

Figure 4 is an end view of the spread limiting clip.

30 Referring now more particularly to the drawing the stretcher is formed of a single length of relatively heavy wire bent medially upon itself to provide the spaced legs 1 and 2 connected by the relatively narrow or sharply bent bight 3 and diverging therefrom. The device is preferably, though not necessarily formed of spring wire and the legs 1 and 2 are spring set to normally move apart.

40 At its outer end the leg 1 is bent laterally toward the other leg 2 as shown at 4 for some distance and is then bent at right angles outwardly as shown at 5 providing a catch 6 terminating in an eye 7 disposed at right angles to the plane of the stretcher as a whole. At its outer end the leg 2 is bent laterally inward toward the leg 1 as shown at 8 and extended toward the same for some distance where it is then bent back in alignment and spaced relationship upon itself

as shown at 9. This construction provides the two spaced arms 10 and 11 arranged at right angles to the plane of the legs 1 and 2 between which the catch 6 carried by legs 1 extends as shown. A lock plate 12 is secured around the arm 10 at 13 and extends toward the arm 11 but terminates short of contact therewith. A plurality of spaced notches 14 are provided in the edge of the plate 12 adjacent the arm 11 for the reception of the catch 6 on leg 1 whereby the legs may be locked in any spaced relationship relatively as will be understood. The notches 14 are undercut or enlarged inwardly of their mouths or openings into the edge of the plate 12 as shown at 15 the better to receive and hold the said catch 6. The arm 11 lying next the notched edge of the locking plate 12 normally prevents the escape of the catch 6 from the notches but the said arm may be sprung away from said plate when removal of the catch from the notches is necessary as will be understood. The legs 1 and 2 are of course sufficiently flexible to permit their relative displacement and bending in the adjustment as described. The end of the arm 11 is curved toward the arm 10 adjacent the outer end of the locking plate 12 as shown at 16 there being sufficient space left between the curved end and the plate 12 and arm 10 to permit the passage of the catch 6 when necessary.

45 In the use of the device as described the outer ends of the legs 1 and 2 are drawn together and the stretcher is then slipped into the tie, shown in broken lines 17, through the open end thereof. The outer ends of the legs 1 and 2 are then spread apart until a lateral tension or pull is put upon the tie and the catch 6 engaged with the proper notch 14. The tie is then left on the stretcher a sufficient period to remove the wrinkles or creases as will be understood. A smaller stretcher may be provided for the smaller end of the tie if so desired. The eye 7 serves as a convenient handle for spreading the legs the while the arm 11 is sprung away from the arm 10 to permit the lateral movement of the catch 6 therebetween.

50 In Figures 3 and 4 a spread limiting clip designated generally at 23 is shown the pur-

100

pose of which is to allow the relatively wide or great spreading of the legs 1 and 2 immediately adjacent their outer ends while the spread of the remainder of the legs is limited to a relatively lesser degree. This makes the stretcher adaptable for use in stretching ties having the relatively widely flaring ends one of which is shown in the broken lines 18. This clip 23 comprises two flat plates 19 and 20 pivoted together at their inner sides by the rivet 21 with their sides in overlapping relationship. At their outer sides the plates 19 and 20 are curved back upon themselves as shown providing marginal open hooks 22. The clip is arranged at the desired point upon the tie and stretcher with the hooks 22 overlapping the margins of the tie and the legs of the stretcher and the clip then limits the spread of the legs as will be understood. The pivotal connection of the plates 19 and 20 allows them to assume the proper relative angles to fit the legs of the stretcher. This stretcher and clip may of course be made in various sizes to stretch ties of all sizes.

While I have herein set forth a certain preferred embodiment of my invention it is understood that I may vary from the same in minor structural details, not departing from the spirit of the invention and within the scope of the appended claims.

I claim:

1. A device of the kind described comprising a length of material bent upon itself and forming a bight and diverging legs, a catch on the end of one leg, spaced arms on the end of the other leg, the said catch passing between the said arms, a locking plate secured to one of the arms, the said locking plate having spaced notches to receive the said catch.

2. A device of the kind described, comprising a length of material bent upon itself forming a relatively narrow bight portion and diverging legs extended therefrom, an inset catch upon one of the legs, inwardly extended spaced arms upon the other leg, the said catch extending between the said arms, a locking plate secured to one of the said arms, the said locking plate being extended towards the other arm and terminating at its edge short of the same, the said locking plate having spaced notches in its edge to receive the said catch.

3. A device of the kind described, comprising a length of material bent upon itself forming a relatively narrow bight portion and diverging legs extended therefrom, an inset catch upon one of the legs, inwardly extended spaced arms upon the other leg, the said catch extending between the said arms, a locking plate secured to one of the said arms, the said locking plate being extended towards the other arm and terminating at its edge short of the same, the said locking plate having spaced notches in its

edge to receive the said catch, and a clip adapted for engagement with the legs intermediate their ends to limit the spread thereof.

4. In a device of the kind described, in combination with a pair of supporting legs, a spread limiting clip comprising a pair of plates pivotally connected at their inner edges, and marginal open hooks formed on the outer edges of the plates for sliding engagement with the said legs.

5. In a device of the kind described, in combination with a necktie stretcher including spaced legs formed of spring wire and means for spreading one end of the legs, a spread limiting clip comprising a pair of pivotally connected plates, and hooks formed on the plates for sliding engagement with the said legs.

In testimony whereof I affix my signature.

GEORGE B. NESS.
